UNITED STATES PATENT OFFICE.

ALVA J. FISHER, OF EVANSTON, ILLINOIS, ASSIGNOR TO HURLEY MACHINE COMPANY, OF CHICAGO, ILLINOIS, A CORPORATION OF ILLINOIS.

MACHINE HAVING AGITATING MECHANISM.

1,184,088.

Specification of Letters Patent. Patented May 23, 1916.

Application filed August 22, 1911. Serial No. 645,424.

To all whom it may concern:

Be it known that I, ALVA J. FISHER, a citizen of the United States, residing at Evanston, in the county of Cook and State 5 of Illinois, have invented certain new and useful Improvements in Machines Having Agitating Mechanism, of which the following is a specification.

My invention relates to machines provided with agitating mechanism such as, for example, washing machines, ice-cream freezers, churns, etc., and the object thereof is to provide a simple, compact and efficient construction of machine of this character.

One of the principal objects of my invention is to provide within the receptacle, in which the agitation takes place a bearing sleeve for the operating rod or shaft of the agitating mechanism, such sleeve extending 20 above the line of liquid, thereby dispensing with the employment of a stuffing box or the like.

Another principal object of my invention is to provide for the arrangement and support of all of the operating mechanism below the receptacle or vat and substantially within the lines of the supporting legs thereof, thereby leaving the top and sides of the receptacle free of such mechanism.

My invention relates to other novel and advantageous features of construction and mode of operation which will be apparent from the description hereinafter given.

For a definite disclosure of my invention I have shown it embodied in a washing machine but it will be understood that in its broader aspect it is not limited thereto and that I contemplate using the same wherever applicable.

In the drawings Figure 1 is a side elevation of a washing machine with a wringer attached illustrating one embodiment of my invention; Fig. 2 is a side elevation of the same machine taken at an angle of 90° with 45 respect to the elevation of Fig. 1; Fig. 3 a section on the line 3—3 of Fig. 2 but on a somewhat larger scale; Fig. 4 a sectional plan on the line 4—4 of Fig. 3; Fig. 5 a detail of a portion of the operating mechanism; Fig. 6 a section on the line 6—6 of Fig. 3; Fig. 7 a section on the line 7—7 of Fig. 4 and Fig. 8 a sectional elevation of the parts shown in Fig. 7.

Referring to the particular embodiment of my invention shown in the drawings, the 55 washing receptacle or vat 1, which may be of any suitable shape and dimensions, is supported some distance above the floor by means of the legs 2, preferably provided with casters 3. This receptacle is open at 60 its top but normally closed by means of a lid or cover 4. Within the receptacle is located a suitable agitating device which is here shown as a dolly bar 5 having a series of depending portions or fingers 5^a and 65 adapted to be agitated by oscillation imparted by the agitating mechanism herein-after described. This bar is mounted to slide upon a bearing sleeve 5^b, which is itself secured to an upright operating shaft, or 70 rod, 6 in a suitable manner as by means of pin 6^a, which fits over and downwardly upon an elongated bearing sleeve 7. This sleeve is of the peculiar formation clearly illustrated in Fig. 3, wherein it is seen that it is provided intermediate its length with a foot portion or flange 7^a secured in suitable manner to the bottom 1^a of the receptacle or vat, as by means of the bolts 8. This sleeve is extended below said flange portion so as to 80 project through a central opening in said bottom. In securing this sleeve to the bottom a washer 9 is preferably employed. This sleeve is made of such a length as to project above the usual water line of the 85 receptacle so as to avoid any possibility of water overflowing the top of the sleeve and flowing downwardly between it and the operating rod or shaft 6. As a result of this construction it is entirely unnecessary to 90 employ a stuffing box, which is objectionable and unsatisfactory in machines of this character.

The mechanism for operating the agitating device through the medium of the vertical rod 6 is compactly constructed and arranged and located in the open space below the receptacle and within the confines of the supporting legs of such receptacle. Moreover all of said mechanism is supported 95 upon a single base plate or bed 10 which is itself screwed to the legs 2 of the machine. As shown, I prefer to employ as the prime mover an electric motor 11 mounted on said base although it will be understood 100 on said base although it will be understood 105 that any other source of power may be em-

ployed. The motor is operatively connected by means of a belt 12 with a large pulley 13 secured to a shaft 14 which is mounted in suitable bearings 15 on the base plate. This 5 shaft is provided at one end with a pinion 16 which in turn meshes with a large gear 17 secured to a shaft 18 mounted in suitable bearings 19 on the base plate. The gear wheel 17 is provided with a crank 20 connected by means of a link or connecting rod 21 with a horizontal reciprocating rack bar 22. This bar is adapted to slide in the two slotted posts or standards 23 and 24, the former of which has provision for vertical 10 adjustment in the manner indicated in detail in Figs. 7 and 8 wherein it is seen that the post is provided with the two anti-friction rollers 25 bearing upon the top and bottom respectively of the rack bar and 15 adapted to be adjusted vertically in the slot 23^a and be clamped in adjusted position by means of the nut 25^a. The outer end of the bar 22 is pivotally connected to the rod 21 while its inner end is formed as a rack, as 20 shown at 22^a in Fig. 4. This rack meshes with a horizontal pinion 26 which is secured to the vertical operating rod or shaft 6. The result of these operating connections is to 25 transform the rotary movement of the electric motor to an oscillating movement of the rod or shaft 6. The rotary movement is imparted by the operating connections hereinbefore described to the gear wheel 17, whose crank imparts a reciprocating movement 30 to the bar 22, which latter movement is imparted to the pinion 26 to provide the oscillating movement of the rod 6.

Upon the same plate I provide operating 35 connections including a reversing mechanism for driving a wringer 27 which is here shown as secured to the top of the receptacle or vat. As clearly shown in Fig. 4, the shaft 18 is extended to the right and carries loosely mounted thereon a sprocket wheel 28 and 40 also a gear wheel 29. The hub of the sprocket wheel is provided with a suitable number of clutch lugs 28^a and likewise the hub of the gear wheel 29 is provided with similar lugs 29^a, such lugs facing each other. 45 Splined to the shaft 18 at a point between the sprocket wheel and gear wheel is a laterally movable clutch 30 which has clutch lugs 30^a on its opposite sides adapted to engage the lugs 28^a and 29^a accordingly as it 50 may be shifted from its neutral position shown in Fig. 4 to an engaging position in one direction or the other. Assuming that the clutches move to the left (Fig. 4) and the clutch lugs 28^a and 30^a are thereby engaged, the sprocket wheel 28 is rotated and such movement is transmitted by means of a sprocket chain 31 to a sprocket wheel 32 which is mounted on a shaft 33 journaled in a bearing 34 on the base plate. This latter

shaft carries at its outer end a sprocket 65 wheel 35 which is operatively connected by means of the sprocket chain 36 with a sprocket wheel 37 on the wringer. The wringer will now be operated in a certain direction when the clutch is thus engaged 70 with the lugs 28^a. If, however, the clutch 30 is moved to the right (Fig. 4) and the lugs 29^a and 30^a thereby engaged the pinion 29 will be rotated thereby, rotating a similar pinion 38 which is secured upon the shaft 75 33. When the clutch is thus engaged the shaft 33 and consequently the wringer will be operated in the reverse direction, it being understood that at this time the sprocket wheel 28 will rotate idly just as did the pinion 29, when the sprocket wheel 28 was being positively driven. The reversing clutch may have any desired shifting mechanism such as the vertical rod 39 arranged to be oscillated by the handle 39^a and operatively 80 connected with the link 40 which is itself connected directly with the clutch shifter 41.

By the use of my invention I am able to provide a machine of the class described which is novel and efficient and which is 90 moreover comparatively simple in construction and not liable to get out of order. Moreover the machine is compactly built and self-contained and arranged with the operating mechanism occupying space which 95 would otherwise be useless and leaving the top of the machine free from operating mechanism except the wringer when the same is used in connection with a washing machine. Furthermore I dispense with all 100 stuffing boxes and the like by provision of the sleeve which not only affords a long bearing for the upper end of the operating rod 6 but also prevents the water from leaking past such shaft. In addition to this bearing in the sleeve the lower end of the shaft is provided with a substantial and comparatively long bearing 10^a rising upwardly from the base plate as clearly indicated in Fig. 3. The shaft is thereby held in perfect 110 alinement.

I claim:

1. In a machine of the class described, the combination of a receptacle, an agitating device therewithin, an oscillating shaft extending vertically through the bottom of the receptacle and operatively connected with said device, mechanism including a prime mover for actuating the shaft, and a plate forming the sole support for said mechanism and detachably connected with said receptacle, said plate being arranged below and within the lines of the receptacle.
2. In a machine of the class described, the combination, with a receptacle and its supporting legs, of an agitating device within the receptacle, an oscillating shaft extending vertically through the bottom of the recep-

tacle and operatively connected with said device, mechanism for actuating the shaft, and a plate forming the sole support for said mechanism and arranged below and 5 within the lines of the receptacle, said plate being detachably secured to said legs of the receptacle and the same and the mechanism

supported thereby constituting a unit which is bodily attachable to and detachable from said legs.

ALVA J. FISHER.
